UNITED STATES PATENT OFFICE.

FRANK E. KENNEY, OF PORTLAND, OREGON, ASSIGNOR OF ONE-HALF TO FRANK A. SWEENEY, OF PORTLAND, OREGON.

STUMP-PULLER.

1,313,545.

Specification of Letters Patent.

Patented Aug. 19, 1919.

Application filed October 29, 1917. Serial No. 199,374.

To all whom it may concern:

Be it known that I, FRANK E. KENNEY, resident of Portland, in the county of Multnomah and State of Oregon, have invented 5 a new and useful Improvement in Stump-Pullers, of which the following is a specification.

This invention relates to improvements in stump pullers and more particularly to 10 improvements in devices for clamping and holding wire cables that are used for pulling stumps.

One object of the invention is to provide 15 a device for gripping and holding a wire cable, that is simple in construction and operation, that will grip the cable securely and effectively without damaging the same, and that will automatically release the cable when the tension thereon is relieved.

20 The invention contemplates the use of a hydraulic cylinder, to furnish power for pulling the stumps, but this part of the apparatus is not herein described in detail since this application is limited to the cable 25 grip or stump pulling device, which may be used with various other forms of power developing apparatus.

The invention consists in the novel construction, adaptation and combination of 30 parts, as will be more clearly hereinafter described and claimed.

In the accompanying drawings, Figure 1 is a somewhat diagrammatic view in elevation of this device as it may appear when in 35 use; Fig. 2 is a view with the top frame plate removed, showing the cable gripping devices partly in plan and partly in cross section; Fig. 3 is a view in side elevation of the device shown in Fig. 2; and Fig. 4 40 is a view partly in section and partly in elevation on broken line 4.4 of the device shown in Fig. 2.

Referring to the drawings throughout 45 which like reference numerals indicate like parts, the numeral 7 indicates a tractor frame that is mounted on wheels 8, and carries an elongated hydraulic cylinder 9, which is provided with suitably arranged piston and fluid inlets and outlets, not 50 shown, whereby fluid under pressure may be utilized to move a piston rod 10.

The above parts are only illustrated and described in a general way as being one form of apparatus for developing power

with which the cable grip herein disclosed 55 may be advantageously used.

The rod 10 terminates in a fixedly mounted body 11 and the cable gripping device comprises two arms 12 that are secured by bolts 13 to the opposite parallel sides of the 60 body 11 and extend forwardly in upwardly inclined diverging relation on opposite sides of two plates 14 and 15 that are rigidly secured to each other in spaced apart relation by pins or bolts 16. 65

Disposed between the plates 14 and 15 are two gripping jaws 17 and 18, that extend parallel with the piston rod 10 in substantial alignment therewith, and are provided on their inner edges with longitudinally extending grooves 19 for the reception of the cable 20. The grooves 19 are corrugated, as indicated at 21, to insure a better gripping contact with the twisted wire cable 20. 70

The gripping jaws 17 and 18 are provided 75 on the edges opposite the grooves 19 with recessed portions 22, that are adapted for the reception of cam surfaces 23 on the ends of lever arms 24 and 25 that are pivotally mounted on pins 26 that extend through the 80 plates 14 and 15.

The lever arms 24 and 25 extend outwardly through bifurcated portions 27 in the ends of the arms 12, and are provided at their outer extremities with pins 28. 85

The pins 26 are held in position by a long key 29 that extends through both of such pins above the plate 14 and by two short keys 30 that extend through the pins 26 below the plate 14 and are secured to such 90 plate by cap screws 31.

The front ends of the arms 12 are rigidly secured in spaced apart relation by an upwardly arched bar 32 and a downwardly arched plate 33, the end 34 of the bar 32 95 passing downward through suitable holes in the extremities of the arms 12 and the ends of the plate 33, so that the arms 12, bar 32 and plate 33 are rigidly secured together to form a frame within which the 100 cable gripping devices are loosely or floatingly disposed.

The gripping jaws 17 and 18 are loosely held within the plates 14 and 15 by the pins 16 and lever arms 24 and 25. 105

When a pull is exerted on the cable 20 in the direction indicated by the arrow A, the cams 23 will engage the recessed por-

tions 22 of the jaws 17 and 18 and move such jaws inwardly into gripping contact with the cable, the outer ends of the lever arms 24 and 25 engaging with the down turned ends 34 of the cross bar 32.

It is obvious that the greater the tension on the cable 20, the more tightly it will be gripped by the jaws 17 and 18.

The cable 20 may be secured directly to the stump that is being pulled, or it may be passed through a tackle block 35, as shown in Fig. 1, and one end secured to a fixed support, the tackle block being secured to the stump 36 by a short cable 37.

It is obvious that changes in the form of construction of the several parts of this device may be made within the scope of the following claims.

What I claim, and desire to protect by Letters Patent, is:—

1. In a stump puller, a cable, a frame, means to reciprocate said frame, and a gripper for said cable loosely arranged in said frame, said gripper including a pair of movable clamping jaws and pivoted actuating cam levers therefor, said levers having their free ends arranged in the path of a part of said frame whereby said levers are swung to move said movable clamping jaws into clamping engagement with said cable when the frame is moved in one direction, said free ends of said levers being arranged in the path of another part of said frame whereby said levers are swung to release said jaws from said cable when the frame is moved in the opposite direction.

2. In a stump puller, a body having opposite flat sides, means to reciprocate said body, a pair of spaced arms rigidly fastened to the opposite flat sides of said body and extending forwardly from the latter in spaced relation,

oppositely bowed arch members rigidly connecting the forward free ends of said arms, and a cable gripping device including a frame loosely disposed between said arch members, said cable gripping device including a pair of spaced plates having a pair of gripping jaws loosely arranged therebetween, and cam levers pivotally mounted between said plates to actuate said clamping jaws, the opposite free ends of said cam levers being operatively connected to said arms whereby movement of the body in one direction will cause said levers to move the clamping jaws toward each other and movement of said body in an opposite direction will cause said levers to free said jaws for movement away from each other.

3. In a stump puller, a body having opposite flat faces, means to reciprocate said body, a pair of arms secured to the opposite flat faces of said body and extending forwardly from the latter in spaced relation, the free ends of said arms being bifurcated, an upper arch member connecting the free ends of said arms and extending through the latter, a lower oppositely bowed arch member connected to the ends of the upper arch member below said arms, a pair of spaced plates loosely disposed between said arch members, cable gripping jaws freely carried between said plates, and cam levers pivoted between said plates to move said jaws having their free ends extended through the bifurcations of said arms, substantially as described.

Signed by me at Seattle, Washington, this 17th day of October, 1917.

FRANK E. KENNEY.
